Primary Examiner — Jennifer L Rempfer*Assistant Examiner* — Adrienne Corna(74) *Attorney, Agent, or Firm* — Terence P. O'Brien(57) **CLAIM**

The ornamental design for a footwear article, as shown and described.

DESCRIPTION

FIG. 1 is a front, side perspective view of a footwear article; FIG. 2 is a front view thereof;

FIG. 3 is a rear view thereof;

FIG. 4 is a first side view thereof;

FIG. 5 is a second side view thereof; and,

FIG. 6 is a top view thereof.

The broken lines depict portions of the footwear article that form no part of the claimed design.

1 Claim, 5 Drawing Sheets(56)
